United States Patent [19]

Ryan et al.

US00D337492S

[11] Patent Number: Des. 337,492

[45] Date of Patent: ** Jul. 20, 1993

[54] FOLDING SPANNER WRENCH

- [75] Inventors: **Bobby W. Ryan, Alanson; David Ivey, Harbor Springs; Thomas D. Sullivan, Cheboygan, all of Mich.**
- [73] Assignee: **Ryan Engineering & Design Co., Inc., Pellston, Mich.**
- [**] Term: **14 Years**
- [21] Appl. No.: **676,737**
- [22] Filed: **Mar. 28, 1991**
- [52] U.S. Cl. **D8/21; D8/105; D8/26; D8/89**
- [58] Field of Search **D8/21, 26, 88, 89, 105; 81/119, 176.1, 177.6; 7/138, 166**

[57] CLAIM

The ornamental design for a folding spanner wrench, as shown and described.

DESCRIPTION

FIG. 1 is a perspective view of a folding spanner wrench in accordance with the design and shown in the open position;

FIG. 2 is a side elevational view of the folding spanner wrench of FIG. 1, the opposing side being a mirror image thereof;

FIG. 3 is a top view of the folding spanner wrench of FIG. 1;

FIG. 4 is a left end elevational view of the folding spanner wrench of FIG. 1;

FIG. 5 is a right end elevational view of the folding spanner wrench of FIG. 1;

FIG. 6 is a bottom view of the folding spanner wrench of FIG. 1;

FIG. 7 is a perspective view of the folding spanner wrench of FIG. 1 and shown in the closed position;

FIG. 8 is a side elevational view of the folding spanner wrench of FIG. 1 and shown in the closed position, the opposing side being a mirror image thereof;

FIG. 9 is a top view of the folding spanner wrench of FIG. 1 and shown in the closed position;

FIG. 10 is a left end elevational view of the folding spanner wrench of FIG. 1 and shown in the closed position;

FIG. 11 is a right end elevational view of the folding spanner wrench of FIG. 1 and shown in the closed position; and,

FIG. 12 is a bottom view of the folding spanner wrench of FIG. 1 and shown in the closed position.
